(57) **CLAIM**

The ornamental design for a receptacle for adapting an outdoor planter to indoors, as shown and described.

DESCRIPTION

FIG. 1 is an exploded top perspective view of a receptacle for adapting an outdoor planter to indoor.

FIG. 2 is a top perspective view, showing the receptacle coupled to a planter.

FIG. 3 is a front perspective view thereof.

FIG. 4 is a front view thereof. The back view, the left view and the right view are mirror images of the front view.

FIG. 5 is a cross-sectional view thereof, with the section cut taken along the center of the receptacle.

FIG. 6 is a top view thereof; and,

FIG. 7 is a bottom view thereof.

The broken lines shown in FIG. 1 and FIG. 2 illustrate environmental structure and form no part of the claimed design.

The broken lines in FIG. 5 depict portions of the receptacle for adapting outdoor planter to indoor and form no part of the claimed design.

1 Claim, 6 Drawing Sheets
